US0D1080535S

(12) **United States Design Patent** (10) **Patent No.:** **US D1,080,535 S**
(45) **Date of Patent:** **** Jun. 24, 2025**

(54) **MODULAR TABLET CHARGING STATION**

(71) Applicant: **Scosche Industries, Inc.**, Oxnard, CA (US)

(72) Inventors: **Yasuhiro Yamamoto**, Thousand Oaks, CA (US); **Kevin Trejo**, Oxnard, CA (US); **Vince Alves**, Oxnard, CA (US); **Mark Larson**, Camarillo, CA (US)

(73) Assignee: **Scosche Industries, Inc.**, Oxnard, CA (US)

(**) Term: **15 Years**

(21) Appl. No.: **29/874,057**

(22) Filed: **Apr. 13, 2023**

(51) LOC (15) Cl. **13-02**

(52) U.S. Cl.

USPC **D13/108**

(58) **Field of Classification Search**

(57) **CLAIM**

The ornamental design for a modular tablet charging station as shown and described.

DESCRIPTION

FIG. 1 is a front upper perspective view showing a modular tablet charging station with separated endcaps;

FIG. 2 is a front lower perspective view showing a modular tablet charging station;

FIG. 3 is a top view thereof;

FIG. 4 is a front view thereof;

FIG. 5 is a right side view thereof;

FIG. 6 is a left side view thereof;

FIG. 7 is a rear view thereof;

FIG. 8 is a bottom view thereof; and,

FIG. 9 is a front perspective view showing a modular tablet charging station with endcaps attached.

In the drawings, the broken line showings are for purposes of illustrating portions of a modular tablet charging station that form no part of the claimed design.

1 Claim, 6 Drawing Sheets
